(57) **CLAIM**

The ornamental design for a multi-pocketed purse, as described and shown.

DESCRIPTION

FIG. 1 is a perspective view of a multi-pocketed purse illustrating my new design;

FIG. 2 is a front elevation view showing the flap in a closed position;

FIG. 3 is a front elevation view showing the flap in an open position;

FIG. 4 is a rear elevation view thereof;

FIG. 5 is a side elevation view thereof;

FIG. 6 is a bottom plan view thereof; and,

FIG. 7 is a top plan view thereof.

The strap is shown detached in FIGS. 2-7 for ease of illustration.
